(57) **CLAIM**

The ornamental design for a mountable toothbrush/razor holder, as shown and described.

DESCRIPTION

FIG. 1 is a perspective view of a mountable toothbrush/razor holder showing the new design;

FIG. 2 is a side view thereof;

FIG. 3 is a front view thereof;

FIG. 4 is a top view thereof;

FIG. 5 is a back view thereof; and,

FIG. 6 is a bottom view thereof.

The broken lines shown in the drawings form no part of the claimed design. The shading shown in the drawings is provided merely to indicate the contour of the design; it is not intended to be indicative of any particular texture, etc.
